UNITED STATES PATENT OFFICE.

BERNHARD SETTEGAST, OF KIEL, GERMANY, ASSIGNEE TO SIGNAL GESELLSCHAFT
MIT BESCHRÄNKTER HAFTUNG, OF KIEL, GERMANY, A FIRM.

SWITCHING DEVICE.

Application filed December 22, 1924, Serial No. 757,468, and in Germany August 26, 1924.

The object of the invention is an electrical switching device with cylindrical contact pieces which are fastened to their carriers so that they are movable for the purpose to obtain between corresponding contact pieces a contact face of as large as possible size.

According to the invention the contact pieces are hollow and contain a helical spring to which the body of the contact piece is fastened. The ends of the spring are secured to a fork shaped carrier of the contact piece.

The object of the invention is shown as an example in the drawing in which

Fig. 1 shows a side elevation of the contact device,

Fig. 2 an elevation at right angles to Fig. 1 and

Fig. 3 a top plan view with a sectional view of the contact piece itself.

The movable part 1 of the switching device is mounted on a bracket 2 by means of a shaft or journal 3 and may be held in one of its extreme positions by a spring 4. The hollow cylindrical contact piece 5 is arranged at the top end of the part 1 by means of the helical spring 6 in the central axis of the contact piece. As shown in Fig. 3 only a central portion of the inner face of the contact piece is in contact with the helical spring the outer ends of 5 being able to move freely in all directions around this central portion. In this way the outer face of 5 can touch the corresponding cylindrical contacts 7 and 8 over a line along the whole length of the contact pieces.

The corresponding fixed contact pieces 7 and 8 may be of prismatic form having plane faces 7' and 8', since such faces insure good contact between the contact members. In the event that one of the contact faces of the prisms becomes injured or covered with a film of oxide, the prism may be turned about the shaft 9, thus presenting a new face to the movable contact.

The contact arm 1 may be actuated by hand, by an electromagnet, or in any other manner known in the art. According to the invention, one or all of the contacts may be arranged upon resilient supports, if desired, although such mounting is shown in the specification only with respect to the mov-

able contact. Furthermore, the invention is not limited to the use of helical springs for the support of the contact pieces, but any other kind of resilient or yielding support may be employed.

I claim:

1. In a switching device, a contact roller having a short concentric bearing, a helical spring acting as a shaft in the bearing, short studs fitting in the ends of said spring, and a forked arm having two prongs near the ends of which said studs are mounted.

2. In a switching device a forked lever arm, a resilient shafting between the forks of said arm, a contact having a short bearing at its center, said resilient shafting passing freely through the bearing and supporting said contact.

3. A switching device comprising a stationary contact, a movable contact member, a short axial bearing through said movable contact member, resilient axial means supporting said contact member only in said short bearing and means, adapted to be moved, for supporting said resilient means and moving said movable contact member.

4. A switching device comprising a stationary contact, a movable contact having an axis substantially parallel to said first contact, an axial bearing through said movable contact comparably short in length with respect to the length of said contact surface, resilient axial means supporting said contact member only in said short bearing and means, adapted to be moved, for supporting said resilient means and moving said movable contact member.

5. A switching device comprising a stationary prismatic contact adapted to be turned, a movable contact member having an axis substantially parallel to the axis of said first contact, an axial bearing through said movable contact comparably short in length with respect to the lengths of said contact surfaces, resilient means supporting said contact member only in said short axial bearing and means adapted to be moved for supporting said resilient means and moving said movable contact member.

In testimony whereof I affix my signature.

BERNHARD SETTEGAST.
